UNITED STATES PATENT OFFICE.

LOUIS B. LARSEN, OSCAR J. HOLMES, AND HANS G. LARSEN, OF CHICAGO, ILLINOIS,
ASSIGNORS TO ACME MOTION PICTURE PROJECTOR COMPANY, A CORPORATION OF
ILLINOIS.

MOTION-PICTURE MACHINE.

1,283,224.

Specification of Letters Patent. Patented Oct. 29, 1918.

Application filed November 8, 1917. Serial No. 200,879.

To all whom it may concern:

Be it known that we, LOUIS B. LARSEN, OSCAR J. HOLMES, and HANS G. LARSEN, citizens of the United States of America, and residents of Chicago, in the county of Cook, State of Illinois, have invented certain new and useful Improvements in Motion-Picture Machines, of which the following is a specification.

10 This invention relates to that class of portable motion picture machine in which the film feeding mechanism, film reels and illuminating means are disposed in a closed and readily portable casing, and has for its 15 object:—

To provide a simple and efficient structural formation and combination of parts whereby an effective ventilation of the lamp house and other heat producing parts, is attained, thus permitting of an increased illumination and a compact and convenient arrangement of the associated parts of the machine, all as will hereinafter more fully appear.

25 In the accompanying drawings:—

Figure 1. is a side elevation of a motion picture machine embodying the present improvement, a hinged side wall or door of the inclosing casing being shown in an open 30 condition and in section.

Fig. 2, is a detail longitudinal sectional elevation on line x^2-x^2 , Fig. 3.

Fig. 3, is a detail transverse sectional elevation on line x^3-x^3 , Fig. 2.

35 Like reference numerals indicate like parts in the several views.

Referring to the drawings, 1 designates the main or inclosing casing of the machine, preferably of the rectangular box form 40 shown, and having a hinged side wall or door 2 for convenient access to the contained mechanisms and parts of the machine.

38 designates the lamp house or inclosure, arranged in the upper and rear portion of 45 the casing 1 and adapted to house the incandescent electric lamp 4 by which the illumination of the machine is provided. In the construction shown the bottom wall of the lamp housing 1 is formed by a laterally removable plate 3' which in turn carries a depending socket 4' adapted to receive the lamp 4 aforesaid.

50 5 designates the optical condenser, and 6 designates the objective of the apparatus, of

any usual and suitable type and aligned with 55 each other and with the filament of the lamp 4, as usual in the present class of machines.

7 designates an operating shaft extending out through the top wall of the casing 1, and provided at its outer end with an operating 60 handle or knob for convenient manual rotation. At its inner end the shaft 7 has crank and pitman connection 8 with the movable member of the objective 6 for effecting a focusing adjustment of said objective.

65 9 designates the fixed apertured film guide or plate by which the picture film is guided transversely through the optical center of the machine in proper spaced relation to the rear portion of the objective 6 aforesaid. Said film guide 9 and the associated film feeding mechanism may be of any ordinary and suitable construction, but are preferably of the construction shown in the drawings, and which forms the subject matter of 70 a prior application for Letters Patent, Serial No. 196,129, filed October 12, 1917, and consisting as follows:—

75 10 designates a track frame secured to a side wall of the casing 1, and to which the aforesaid film guide or plate 9 is fixedly attached by a lateral carrying bracket 11 as shown. The track frame 10 also carries lateral brackets or posts to the ends of which are secured upper and lower longitudinally 80 disposed tracks or slideways 12 for the guidance of the hereinafter described carriage of the film feeding mechanism in a direction parallel to the optical axis of the machine.

85 12 designates the carriage above referred 90 to, preferably of the plate form shown, and having sliding engagement with the aforesaid tracks or slideways 12.

95 14 designates an operating shaft journaled on the track frame 10 and carrying a pinion 15 having operative engagement with a rack bar on the carriage 13 aforesaid, and adapted to effect a longitudinal adjustment of said carriage. The end of the shaft 14 opposite to that carrying the pinion 15 extends out through the top wall of the casing 1, and is provided with a handle or knob for convenient manual actuation.

100 16 designates the driving shaft by which the intermittent film feeding mechanism and the light shutter of the machine are operated in unison. The shaft 16 is journaled in the carriage 13, and in addition to the

usual gearing connection 17 with an operating shaft capable of manual rotation, has power connection by pulley and endless belt 19 with an electric motor 20 arranged in the 5 lower and rear portion of the casing 1. In the structure shown, the electric motor 20 in addition to affording driving power for the film feeding mechanism as above set forth, also furnishes power for operating the film 10 take-up and film rewinding mechanisms hereinafter referred to and the details of which constitute the subject matter of a separate application for Letters Patent, Serial No. 200,877, filed Nov. 8, 1917.

15 21 designates the light shutter before referred to, preferably of the radial bladed type and carried by a shaft 22 journaled longitudinally on the carriage 13 aforesaid, so as to be adjusted longitudinally therewith, 20 and is provided at its rear end with gearing connection 23 with the driving shaft 16 above described.

24 designates the intermittent film feeding sprocket drum journaled in the carriage 13 aforesaid, in operative relation to the lower end of the film guide 9, and carrying the driven element of an intermittent gearing device such as the ordinary Geneva movement 25 shown in Fig. 1, the driving element 30 of said intermittent gearing being fixed to the operating shaft 16 aforesaid.

26 designates the sprocket drum by which the usual free loop in the picture film is maintained at the upper and entrance end 35 of the film guide or plate 9. The carrying shaft of said drum 26 is also journaled in the carriage 13 and receives constant rotation from the shaft 18 through gearing 27. In the preferred construction shown, the 40 sprocket drum 26 is arranged in a plane to one side of the plane in which the intermittent film feeding sprocket drum 24 is arranged and in line with the film delivery reel of the machine, while the aforesaid film 45 feeding sprocket drum 24 is in line with the film take-up reel of the machine in the normal operation of the same as a picture projecting apparatus.

The take-up and delivery reels above referred to are arranged in a magazine or casing 28 located in the forward and lower portion of the inclosing casing 1 of the machine, and are preferably of the construction and arrangement described in detail in separate applications for Letters Patent, Serial 55 Nos. 200,877 and 200,878, filed Nov. 8, 1917.

29 designates a pair of idler drums journaled in the upper and forward end of the main casing 1 in horizontal spaced relation 60 to each other, and disposed in oblique relation to the optical center of the machine, as shown in Fig. 1. As so arranged the drums 29 are adapted to maintain an oblique loop in the picture film, after the same has been 65 unthreaded from the intermittent film feed-

ing mechanism and apertured film guide heretofore described, and placed over said drums 29, in the operation of changing the mechanisms from an exhibiting condition to a film rewind condition.

A material feature of the present invention involves means for ventilating and cooling the lamp house 3, and parts adjacent thereto, and consists as follows:

30 designates a series of apertures formed in the lower wall or bottom plate of the lamp house 3 aforesaid, and 31 designates a corresponding series of apertures formed in the top wall of said lamp house.

32 designates an apertured baffle plate arranged in spaced relation above the top wall of the lamp house 3 aforesaid, and below a grated opening 33 in the top wall of the main casing 1, as shown in Figs. 2 and 3. With the above described construction a free 85 upward circulation of air can take place through the main casing 1 and lamp house 3, to carry off the radiant heat from the illuminating means employed in the continued actual use of the machine.

34 designates a rotary fan arranged in operative relation to the electric motor 20, and operatively connected with the power shaft of said motor by pulley and belt connection 35, so that in the operation of said motor a 95 forced upward current of air will be produced by the fan 34 and in the passage of said air through the lamp house, etc., an effective cooling of parts will be attained.

36 designates side spaces separating the 100 side walls of the lamp house 3 from the side walls of the main casing 1.

37 designates grated openings in the side walls of the main casing 1, near the upper ends of the side spaces 36 aforesaid, for the 105 escape of heated air from the interior of the main casing 1.

The above described arrangement of the side spaces 36, and openings 37, in connection with an opening 38 in the bottom wall 110 of the casing 1, is adapted to afford effective ventilating conditions and maintain the motor 20 and its associated electrical resistance element or rheostat 21 in a properly cooled and effective condition.

Having thus fully described our said invention, what we claim as new and desire to secure by Letters Patent, is:—

1. In a portable motion picture machine, the combination of a closed rectangular casing, a lamp house arranged in the upper rear portion of said casing and provided with upper and lower ventilating openings, a film feeding mechanism and associated optical system located in front of the lamp house and in the upper forward portion of the casing, a reel magazine located in the lower forward portion of said casing, and a motor located in the lower rear portion of said casing, and having operative connec- 130

tions with the film feeding mechanism and with the film reeling mechanism of the magazine aforesaid, substantially as set forth.

- 5 2. In a portable motion picture machine, the combination of a closed rectangular casing, a lamp house arranged in the upper rear portion of said casing and provided with upper and lower ventilating openings, 10 a film feeding mechanism and associated optical system located in front of the lamp house and in the upper forward portion of the casing, a reel magazine located in the lower forward portion of the casing, a motor 15 located in the lower rear portion of the casing and having operative connections with the film feeding mechanism and with the film reeling mechanism of the magazine, and a fan or blower arranged beneath the 20 lamp house and having operative connections with said motor, substantially as set forth.
3. In a portable motion picture machine, the combination of a closed rectangular casing, a lamp house arranged in the upper rear portion of said casing and having a less width than said casing to provide spaces between the respective side walls of said casing and lamp house, the side walls of the 25 casing having openings communicating with said side spaces, and a film feeding mechanism and associated optical system located in front of said lamp house, substantially as set forth.
- 30 4. In a portable motion picture machine, the combination of a closed rectangular casing, a lamp house arranged in the upper rear portion of said casing and having a less width than said casing to provide spaces 35 between the respective side walls of said casing and lamp house, the side walls of the casing having openings communicating with said side spaces, a motor arranged in the lower rear portion of the casing, and a fan or blower arranged beneath the lamp 40 house and having operative connections with said motor, the lamp house having upper and lower ventilating openings, substantially as set forth.
- 45 5. In a portable motion picture machine, the combination of a closed rectangular casing, a lamp house arranged in the upper rear portion of said casing and having a less width than said casing to provide spaces 45 between the respective side walls of said casing and lamp house, the side walls of the casing having openings communicating with said side spaces, a motor arranged in the lower rear portion of the casing, and a fan or blower arranged beneath the lamp house

and having operative connections with said motor, substantially as set forth.

5. In a portable motion picture machine, the combination of a closed rectangular casing, a lamp house arranged in the upper 50 rear portion of said casing and having a less width than said casing to provide spaces between the respective side walls of said casing and lamp house, the side walls of the casing having openings communicating with 55 said side spaces, and a film feeding mechanism, the lamp house having upper and lower ventilating openings, substantially as set forth.

6. In a portable motion picture machine, 60 the combination of a closed rectangular casing, a lamp house arranged in the upper rear portion of said casing and having a less width than said casing to provide spaces between the respective side walls of said casing and lamp house, the side walls of the casing having openings communicating with said side spaces, a motor arranged in the lower rear portion of the casing, and a fan or blower arranged beneath the lamp 70 house and having operative connections with said motor, the lamp house having upper and lower ventilating openings, substantially as set forth.

7. In a portable motion picture machine, 75 the combination of a closed rectangular casing, a lamp house arranged in the upper rear portion of said casing and having an open bottom, a laterally sliding plate fitting said bottom of the lamp house, and provided 80 with a depending socket adapted to receive an incandescent lamp and a film feeding mechanism and associated optical system located in front of the lamp house, substantially as set forth.

Signed at Chicago, Illinois, this 31st day of October, 1917.
